US00D429735S

United States Patent [19]**Versaw, Jr. et al.****Patent Number: Des. 429,735****Date of Patent: ** Aug. 22, 2000**[54] **INTEGRALLY FORMED TANK SUMP WITH LID**[75] Inventors: **Robert H. Versaw, Jr.; James W. Mosier**, both of Muskegon; **Daniel P. Nordstrom**, Twin Lake, all of Mich.[73] Assignee: **Advanced Polymer Technology, Inc.**, Muskegon, Mich.[**] Term: **14 Years**[21] Appl. No.: **29/091,118**[22] Filed: **Jul. 23, 1998****Related U.S. Application Data**

[63] Continuation-in-part of application No. 29/083,576, Feb. 12, 1998, Pat. No. Des. 404,742.

[51] **LOC (7) Cl. 15-02**[52] **U.S. Cl. D15/7**[58] **Field of Search** D15/7-9; 310/87; 73/40, 40.1, 40.5 R, 49.2, 49.5; 285/21; 137/565, 312; 417/411, 424.1, 423.3, 434, 367, 234; 415/199.2[56] **References Cited**

Primary Examiner—Ralf Seifert
Attorney, Agent, or Firm—Young & Basile, P.C.[57] **CLAIM**

The ornamental design for an integrally formed tank sump with lid, as shown and described,

DESCRIPTION

FIG. 1 is an isometric view embodying the ornamental design constituting our invention;
 FIG. 2 is a top plan view thereof;
 FIG. 3 is a front elevational view thereof, which is identical to the rear elevational view;
 FIG. 4 is a bottom plan view thereof; and,
 FIG. 5 is a right-side elevational view thereof, which is identical to the left-side elevational view.
